CARVING DEVICE

Edward A. Farish, Washington, D. C.

Application September 30, 1942, Serial No. 460,247

12 Claims. (Cl. 146—215)

This invention relates to carving devices, and is particularly concerned with an improved type of retaining means or holder for a fowl, roast, or other food product during cooking and/or carving.

An object of the invention is to provide a convenient yet highly effective means for firmly holding the fowl, roast or other food product during the carving operation, and particularly when the carving is to be done at the table while the food product rests on a platter or plate, the unit being of simple construction and readily disassembled to permit a thorough cleaning and sterilization after use.

Another object is to provide a carving device or unit adapted to rest on a plate or platter or other convenient surface and which will automatically resist displacement while at the same time providing a convenient hand grip so that the user may maintain a firm hold on the unit and the article supported thereby during the carving operation.

Another object is to provide a device or unit of the type specified wherein the parts are of simple construction and may be manufactured at a relatively low cost.

A further object is to generally improve and render more effective devices of this general type.

The foregoing and other objects and advantages will become apparent in view of the following description taken in conjunction with the drawing, wherein:

Fig. 1 is a plan view of a carving unit in accordance with the invention;

Fig. 2, a broken side elevation of Fig. 1;

Fig. 3, an end view of the unit; and,

Fig. 4, a detailed plan view of the base member forming part of the unit.

Referring to the drawing in detail, the device comprises a base 5 which is preferably made of relatively thin sheet-like material, such for example as sheet metal, plastic or the like and is formed with a series of holes or openings 6. This base member constitutes an important feature, since it is adapted to rest on a flat surface and should be relatively flexible so as to conform to said surface, the holes acting as non-skid means in that they form release passages or vents for broth, gravy or other fluid which is invariably present in a cooked fowl, roast or the like and which flows by gravity to the bottom of the platter. Actual experience has demonstrated that a base of this type will retain its position with unusual tenacity and resist displacement not only during the carving operation but also

when the platter is being carried from one point to another.

Projecting upwardly from the center of the base is a pointed threaded stud 7 which functions not only as a stud bolt but also as a skewer. This combined stud bolt and skewer 7 is permanently secured to the base in any suitable manner as by welding, or by molding integral with the base, and is adapted to receive a wing nut 8 for a purpose to be described.

Side members 9 and 9a are provided and at their lower edges are each formed with substantially transverse extensions 10 and 10a having open-ended slots 11 and 11a therein adapted to slidably engage over the lower portion of the stud 7. A clamping plate 12 having a central hole or opening therein is adapted to be inserted over the stud 7 and be clamped firmly against the extensions 10 and 10a by means of the wing nut 8. A washer 13 is shown inserted between the wing nut 8 and plate 12, but this obviously may be dispensed with if desired, and in fact it is preferred to construct the base of the wing nut to take the place of a washer and thereby reduce the number of parts.

It will be noted that these side members 9 and 9a project upwardly and outwardly in opposite directions from the base, defining a receiving opening or space of varying capacity, the upper portion of the space being relatively wide and gradually narrowing as it approaches the base. In this manner, a fowl, roast or the like of practically any size may be accommodated and in each instance the gripping action will be relatively firm. These side members may also be formed of sheet metal or other relatively thin, preferably resilient material and each may be readily stamped or otherwise formed as an integral unit.

At an intermediate point along the upper edges of the side members 9 and 9a are located skewer brackets 14 and 14a, each of which preferably consists of upper and lower spaced members formed with holes or openings 15, 15a to receive a skewer pin 16 which projects downwardly through these holes and is adapted to engage the article being carved and hold the latter against displacement with respect to the unit. By referring to Fig. 3, it will be noted that the skewer pin 16 is bent at an angle so that after it has been projected into the fowl or roast, it may be turned to firmly anchor or clamp the fowl tightly against the adjacent side member as well as exert a downward thrust thereon towards the base of the unit.

Preferably, but not necessarily, the lower brack-

et member 14' of each bracket 14, 14a is formed with a plurality of holes to permit the skewer pin 16 to be adjusted at varying angles, the upper hole being of such capacity or size as to permit angular movement of the pin for this purpose.

The side members 9, 9a are provided with finger grips 17, 17a to afford a hold for the operator during the carving operation. These finger grips may, if desired, be integral with the brackets 14, 14a and either permanently or detachably applied or connected to the side members 9, 9a.

The clamp plate 12 and contiguous surface of the base member 5 are formed with registering ribs or indentations 18 to prevent turning movement of the side plates 9, 9a on the base.

From the foregoing, the manner in which the unit is assembled and operates should be readily apparent. Obviously, different methods of handling the unit may be adopted in accordance with the individual using the same. Ordinarily, the base is disposed on a flat surface, such as the bottom of a platter, with the clamping plate 12 loosely disposed on the skewer stud 7. The bottom extensions of the side members are then inserted beneath said plate with the inner open ends of the slots 11, 11a in registration with the bottom of the stud and then slid together in overlapping or partly overlapping relation, depending upon the spacing to be had between the side members. By sliding these side members toward or from one another, the capacity of the unit may be varied to suit practically any size of fowl, roast or the like. The wing nut 8 is then screwed down, securely clamping the side members in position.

While the device can be used during the cooking or roasting operation, it is primarily adapted for carving, the fowl or roast being disposed in the space between the side members with the skewer pin 16 retracted, after which the said pin is thrust downwardly into the fowl and then turned to more firmly engage the latter, note the dotted line position in Fig. 3. The fowl or roast is now ready to be carved, the operator grasping the unit by means of the finger grips 17 or 17a with one hand while carving with the other. Whenever it is desired to turn the fowl or roast to another position for better carving, it is only necessary to retract the skewer pin 16. The device also serves an important function in holding the fowl or roast in a position where it will cook to the best advantage.

The parts of the unit may be readily taken apart and cleaned and sterilized. It is desirable to make the parts devoid of crevices in which food may lodge. The side members and skewer pin are practically the only parts visible when the unit is in use and these may be made with attractive contours and of material which will be pleasing to the eye. The parts in the main are adapted to be stamped out or molded, although any suitable method of manufacture may be adopted. By making the side members of open construction or of wire or rod stock, a minimum of contact with the article being cooked or carved is assured.

It will be understood that no attempt has been made herein to enumerate all the advantages of the unit, and that changes in construction and design may be carried out in accordance with individual requirements without departing from the spirit or scope of the invention as defined by the appended claims.

What is claimed is:

1. A device for retaining a fowl, meat or other

article of food in position on the bottom of a platter or like supporting surface comprising a base of flexible material adapted to conform to said surface, side members projecting upwardly and outwardly in divergent relation from said base and defining therebetween a space for receiving the article, and skewer means adapted to engage the article and hold it against displacement with respect to the unit.

2. A device for holding articles of food such as a fowl, roast or the like in position with respect to the bottom of a platter or other supporting surface comprising a base of flexible material adapted to rest on and conform to said surface, side members connected to said base and projecting upwardly and outwardly in divergent relation therefrom and defining therebetween a space for receiving said article, and skewer means connected to said side members and adapted to be thrust downwardly into the article and hold it against displacement with respect to the device.

3. A device for holding articles of food such as a fowl, roast or the like in position with respect to the bottom of a platter or other supporting surface comprising a base of flexible material adapted to rest on and conform to said surface, side members connected to said base and projecting upwardly and outwardly in divergent relation therefrom and defining therebetween a space for receiving said article, skewer means connected to said side members and adapted to be thrust downwardly into the article and hold it against displacement with respect to the device and means for adjusting said side members toward and from one another to vary the capacity of the device.

4. A device or unit for holding articles of food such as a fowl, roast or the like against displacement with respect to a supporting surface, comprising a base member adapted to rest on said surface, a pointed stud projecting upwardly from said base member and serving as a skewer for the article, side members having lateral extension adapted to engage over said stud, said side members projecting upwardly and outwardly and affording a space therebetween for receiving the article, and means adapted to engage over said skewer stud and clamp against said extensions and adjustably hold the latter in position on said base member.

5. A device or unit for retaining an article of food such as fowl, roast or the like in position with respect to a supporting surface, as for example during carving, comprising a base member of flexible relatively thin material adapted to rest on and conform to said surface, a combined stud and skewer bolt projecting upwardly from said base, side members having bottom lateral extensions formed with elongated openings or slots adapted to slideably engage over said skewer bolt, said side members projecting upwardly and outwardly and defining therebetween a space for receiving the article, clamping means adapted to engage over said bolt and be clamped against said extensions, and a skewer pin connected to said side members and adapted to engage the article and coact with said skewer bolt to hold the article against displacement with respect to the unit.

6. A device or unit for holding an article of food in position with respect to a supporting surface, as for example during carving, comprising a relatively thin flexible base member adapted to rest on and conform to a supporting surface,

side members also of flexible material having bottom lateral extension formed with elongated slots or openings, a skewer bolt secured to said base and projecting upwardly therefrom, said extensions being insertible over said skewer bolt, and a clamping plate adapted to engage over said skewer bolt and be clamped against said extensions, said side members projecting upwardly and outwardly and defining a space therebetween for receiving the article, a bracket connected to the upper portion of at least one of said side members, and a skewer pin adapted to be thrust downwardly through said bracket and into the article.

7. A device or unit for holding an article of food in position with respect to a supporting surface comprising a relatively thin flexible base member adapted to rest on and conform to said supporting surface, side members also of flexible material having bottom lateral extensions formed with elongated slots or openings, a skewer bolt secured to said base and projecting upwardly therefrom, said extensions being insertible over said bolt, a clamping plate adapted to engage over said skewer bolt and be clamped against said extensions, said side members projecting upwardly and outwardly and defining a space therebetween for receiving the article, a bracket connected to the upper portion of at least one of said side members, a skewer pin adapted to be thrust downwardly through said bracket and into the article, said skewer pin being bent off line or at an angle so that it may be turned to more effectively clamp the article against displacement with respect to the adjacent side member.

8. A device or unit for holding an article of food such as a fowl, roast or the like in position on a supporting surface, comprising a relatively thin flexible base member adapted to rest on said surface, a combined skewer and stud bolt projecting upwardly from said base member, a pair of oppositely disposed flexible side plates having bottom lateral extension formed with elongated slots for slidingly engaging over the base of said skewer bolt, brackets connected to the upper edges of said side members and formed with one or more openings or holes, a skewer pin adapted to be projected downwardly through said holes into the article, and finger grips connected to said side members.

9. As an article of manufacture, a device or unit in the form of an assembly for holding an article of food such as a fowl, roast or the like against displacement with respect to a supporting surface as for example during carving, comprising a relatively thin flat flexible base member formed with a plurality of non-skid holes or openings, side plates also of relatively thin flexible material having bottom lateral extensions

- formed with elongated slots, a combined skewer and stud bolt secured to said base member and projecting upwardly therethrough, said side members being assembled to said base by sliding said extensions over said stud bolt in overlapping relation, a clamping plate adapted to be applied over said stud bolt, a wing nut on said stud bolt for tightening down against said clamping plate, skewer brackets connected to the upper edges of said side plates or members, said brackets each having one or more holes or openings formed therethrough, a skewer pin adapted to be projecting downwardly through said openings into the article, and finger grips connected to the upper portion of each of said side plates.
10. A device for holding an article of food such as a fowl, meat roast or the like in position on a supporting surface, comprising a substantially flat base member, a pair of oppositely disposed side members projecting upwardly and outwardly in opposite directions from said base member and defining therebetween a divergent space open from end to end of the device adapted to receive the article of food and grip the latter as it wedges itself into said space, and means connecting the said side members to said base, said side members being provided with finger grips whereby the device may be held stable during carving operations.
11. A device for holding an article of food such as a fowl, meat roast or the like in position on a supporting surface, comprising a substantially flat base member, side members of flexible material projecting upwardly and outwardly in opposed relation and defining therebetween a divergent space adapted to receive the article of food and grip the latter as it wedges itself into said space, and means connecting said side members to said base, said means being constructed and arranged for lateral adjustment of said side members towards and from one another to thereby vary the capacity of the device, said side members being unconnected to one another from the base upwardly permitting free flexing thereof.
12. A device for holding an article of food such as a fowl, meat roast and the like in position against displacement during cooking, carving or the like operations, comprising a relatively thin substantially flat base, a pair of oppositely disposed side members of flexible material secured to said base and projecting upwardly and outwardly therefrom and defining therebetween a divergent space adapted to receive the article of food and grip the latter as it wedges itself into said space, means securing the lower edge portions of said side members to said base, a skewer, and means on said side members for supporting and guiding said skewer.

EDWARD A. FARISH.
